ATTORNEYS

UNITED STATES PATENT OFFICE.

ARTHUR WELLS MINNEY, OF STOCKTON, CALIFORNIA.

WRENCH.

1,391,749.

Specification of Letters Patent. Patented Sept. 27, 1921.

Application filed April 6, 1921. Serial No. 458,917.

To all whom it may concern:

Be it known that I, ARTHUR WELLS MINNEY, a citizen of the United States, and a resident of Stockton, in the county of 5 San Joaquin and State of California, have invented certain new and useful Improvements in Wrenches, of which the following is a specification.

The present invention relates to improvements in wrenches, and has for its object 10 to provide an improved wrench which is of simple and durable construction, reliable in operation, readily adjustable and easy and inexpensive to manufacture, and which 15 is adapted to powerfully grip the object or work and to apply a powerful torque thereto without distorting or breaking the elements of the wrench.

Other objects and advantages of the invention reside in certain novel features of construction, combination and arrangement of parts which will be hereinafter more 20 fully described and particularly pointed out in the appended claim, reference being had 25 to the accompanying drawings forming part of this specification, and in which:

Figure 1 is a side elevational view of the invention;

Fig. 2 is an end elevational view thereof; 30 Fig. 3 is a transverse sectional view on line 3—3 of Fig. 1; and

Fig. 4 is a similar view on line 4—4 of Fig. 1.

Referring to the drawings wherein for 35 the sake of illustration is shown the preferred embodiment of the invention, the numeral 10 designates the body portion of the wrench. The body portion is elongated and has formed therein and extending longitudinally therethrough a slide bearing 11 of polygonal cross section. The body portion is also provided with a transverse opening or recess 12 extending from side to side thereof and intersecting the bearing.

40 An inner jaw 15 is integrally formed with one end of the body portion 10. The outer jaw 16 is arranged in co-operative relation to the inner jaw and these jaws constitute the coacting jaws of the wrench. The outer 45 and inner jaws are provided with laterally enlarged working faces, designated at 15^a and 16^a, respectively.

A shank 18 is integrally formed or otherwise secured to the outer jaw 16. The shank 50 is polygonal in cross section and is slidably received in the bearing 11 of the body por-

tion. The side of the shank adjacent the jaws as well as the corresponding wall of the bearing is slightly greater than the width of the jaws proper so that shoulders 60 19 are provided on the shank, as clearly shown in Fig. 2. An extension bearing 20 is integrally formed with or otherwise secured to the body portion and is aligned and contiguous with the bearing 11. The wall of 65 the extension bearing 20 adjacent the jaws is however open to permit of the requisite movement although this open side of the bearing adjacent this open wall is partially closed by longitudinally extending flanges 70 21 which slidably embrace the shoulders 19 of the shank. In all working positions of the jaws this extension bearing and the flanges embrace the jaws and the shank and maintain the jaws in alinement and in 75 proper engagement with the object or work.

Operating mechanism is provided for the coacting jaws and includes a traveling screw 23 which is integrally formed with or otherwise secured to the shank 18 of the outer 80 jaw 16. The traveling screw is provided with square threads 23^a of relatively great pitch in order to effect speedy adjustment. A nut 24 is rotatably journaled in the bearing provided therefor in the body portion 85 10 and it is provided with a threaded bearing 25 operatively engaged with the traveling screw 23. The upper face of the nut 24 has secured thereto a sleeve 26 which rotatably abuts the adjacent wall of the body 90 portion. A seat 27 is provided for the under face of the nut and serves also as a guard therefor. A plurality of longitudinally extending and spaced ribs 28 is provided on the peripheral face of the nut and 95 these ribs provide a means whereby the nut may be readily turned.

Below the nut the body portion is provided with a tubular extension 10^a which houses and provides a bearing for the screw 100 23 and which also constitutes a hand grip for the wrench.

In practice, the jaws of the wrench may be readily adjusted by means of the ribs 28 of the operating nut 24. The seat 27 105 and the bearing provided in the body portion support the nut and its sleeve 26 so that it may be readily rotated. When the nut is rotated its threaded bearing 25 which is operatively engaged with the traveling 110 screw 23 imparts movement thereto. The shank being secured to the screw receives

- its movement and the movement of the shank as well of the screw is constrained to the rectilinear by virtue of the polygonal bearing 30 and the correspondingly polygonal cross section of the shank. When the jaws are engaged with the object, they may exert a powerful torque thereon without danger of distortion and without impairing the engagement of the jaws with the object.
- 10 This is brought about by virtue of the bearing 20 and its flanges 21 engaging the shank 18 and the shoulders 19 thereof respectively. These parts take up the stresses and maintain the jaws in alinement and consequently 15 in proper engagement with the work.

I claim:

- In a wrench of the character described, a body portion having a longitudinal bearing therein of polygonal cross section and 20 having a recess extending from side to side thereof, a fixed jaw carried by said body portion, a movable jaw coacting with said

fixed jaw, a shank carried by said movable jaw and slidably received in the bearing of said body portion, said shank being of 25 polygonal cross section and having shoulders formed adjacent said movable jaw, an extension bearing carried by the body portion and alined with its bearing and having longitudinal flanges slidably engaging the 30 shoulders of the shank, a traveling screw secured to the shank, a rotatable nut journaled in the recess of the body portion and having a sleeve carried by one face and rotatably abutting the body portion, a seat 35 carried by the body portion and rotatably abutting the other face of the nut, a plurality of ribs carried by the traveling face of said nut, and a tubular extension carried by the body portion and constituting a 40 bearing and housing for the traveling screw and a hand grip for the wrench.

ARTHUR WELLS MINNEY.
